UNITED STATES PATENT OFFICE.

HORACE L. KENT, OF BROOKLYN, NEW YORK.

GOLF-CLUB.

1,213,382.

Specification of Letters Patent. Patented Jan. 23, 1917.

Application filed May 10, 1916. Serial No. 96,526.

To all whom it may concern:

Be it known that I, HORACE L. KENT, a citizen of the United States, residing in the borough of Brooklyn, in the city of New York, county of Kings, and State of New York, have invented certain new and useful Improvements in Golf-Clubs, of which the following is a specification.

My invention relates to golf clubs and it is particularly adapted to a wooden club such as a driver or a brassie.

In clubs of this character it is desirable that the head of the club should be so weighted or provided with ballast material as to suit the different users of the club. It is further desirable that such ballast material can be so positioned and adjusted in the head as to properly balance the club.

One of the objects of the present invention is to provide a construction in which the ballasting and balancing of a golf club can be easily and quickly effected to meet the individual wishes of the user.

One feature of the invention may be realized by providing the head of the club with an adjustable or in some instances with a removable ballast member. The ballast member is eccentrically weighted or loaded with respect to an axis about which it is adjustable and in the preferred form of my invention this ballast member is insertible in the head and can be adjustably positioned therein at will by angular movement about said axis.

Another object of the invention is to construct a golf club with a built-up head.

As illustrating certain specific embodiments of the invention reference is made to the drawings forming a part of this specification and in which drawings,

Figure 1 is a front elevation of a golf club, a portion of the shaft being broken away. Fig. 2 is a vertical sectional view taken as on the plane indicated by the line 45 2-2 of Fig. 1 looking in the direction of the arrows. Fig. 3 is a view looking at the bottom of the club shown in Fig. 1. Fig. 4 is a plan view of the cup member of the club shown in Figs. 1 to 3 in which member the heavy ballast material is contained. Fig. 5 is a front elevation of another form of golf club, a portion of the shaft being broken away. Fig. 6 is a vertical sectional view taken as on the plane indicated by the line 55 6-6 of Fig. 5 looking in the direction of the

arrows. Fig. 7 is a view looking at the bottom of the club shown in Fig. 5. Fig. 8 is a plan view of the cup member of the club shown in Figs. 5 to 7, and Figs. 9 and 10 show screws which can be inserted as ballast material in the cup member shown in Fig. 8.

In both forms of club shown the shaft of the club is designated by A and the striking head by B.

The striking head B, which is preferably made of strong durable wood although it may be made of any other suitable material, is preferably provided with a cylindrical bore as D that is preferably counter-bored as at E to receive the ballast or cup member designated as C in Fig. 4 and as C' in Fig. 8. The ballast or cup member may be secured in place in the bored opening as by means of the screw F (see Fig. 2) which enters the nut or socket G secured in the upper portion of the head B, or it may be secured in place as by the wood screw F' which enters directly into the wooden material of the head. The cup member is preferably cylindrical in form and has a bottom H, and the upwardly extending flanged portion K is provided with a cavity or pocket M (as shown in Fig. 4) or with a plurality of pockets N, O and Q (as shown in Fig. 8) in which ballast material, as L, can be permanently secured. If desired, the ballast or cup members C and C' may also be provided with an additional cavity or receptacle M' as shown in Fig. 4 in order to secure the desired weight and balance.

As the cup member C is preferably of metal it is obvious that lead or other fusible metal may constitute the ballast material, and that the desired amount can be very readily secured in the various cavities or pockets, M, M', N, O and Q as desired by the user of the club. Instead of lead other material can be employed as ballast, for instance ballast in the form of screws x and y can be inserted in and removed from the holes or threaded openings N, O and Q of the cup or ballast member C'. The cup member C or C' while cylindrical in form is eccentrically weighted or loaded and can be revolved or given an angular movement about its axis (to wit, a vertically extending axis) by merely loosening the screw F or F' whereby the heavy weighted or ballasted portion can be given substantially any desired position relative to the striking face 110

- of the club, thus giving any desired ballasting effect. The axis just referred to coincides with the axis of the cylindrical portion of the cup member C or C':
5. The bottom H of the cup member C or C', is preferably made flush with the bottom of the striking head B and the top of the socket member G (if there is such a member) is also preferably made flush with the upper 10 surface of the striking head.
10. It is thus apparent that by my invention the head of a golf club can be weighted or ballasted and also balanced to suit the individual wishes of the user. This end is 15 enabled to be realized because the cylindrical cup member C or C', which can be revolved or angularly adjusted with respect to its axis, has the effective weight of the ballast or loading material eccentric to the axis 20 about which the member is adjustable. By loosening the screw F or F' and revolving the cup member C or C', the weight or ballast can be made to assume any position relative to the striking face of the club. Furthermore, by varying the amount of ballasting 25 material in the cavities or pockets M, M', N, O, and Q the weight of the club can be made to suit the individual wishes of the user.
30. In the form shown in Figs. 5, 6 and 7 the club has a built up head, the main member of which head, to wit, the part P, has secured to it a face member R that may be of material such as lignum-vitæ. The grain of 35 the wood in the face member preferably extends substantially at right angles to the striking face. This face member may be secured in place as by means of a dove-tail joint which passes through it into the body member. A reinforcing shoe S preferably 40 of wood can be employed to strengthen the head and to assist in securing the face member to the body member. The grain of the wood in the shoe should extend in such a 45 direction as will permit it to perform its function, viz., the wood grain should extend from under the face member to under the body member.
- The improvements herein set forth are not 50 limited to the precise construction and arrangement shown and described for they may be embodied in various forms and modifications without departing from the spirit and scope of the invention.
55. What I claim is:
1. A golf club having in the head thereof an angularly adjustable cup member containing ballast material, which material is eccentrically located relative to an axis 60 about which said ballast member is angularly adjustable.
2. A golf club having in the head thereof an angularly adjustable ballast member, which ballast member is unsymmetrically 65 weighted with respect to an axis relative to which said ballast member is angularly adjustable.
3. A golf club having in the head thereof a removable eccentrically-weighted ballast member which can be caused to assume any 70 one of several angularly adjusted positions in the head whereby the effect of the eccentrically weighted ballast member can be regulated.
4. A golf club having in the head thereof 75 an angularly adjustable ballast member detachably secured in the head, which ballast member is eccentrically weighted with respect to the axis about which it is angularly adjustable.
5. A golf club having in the head thereof 80 an angularly adjustable ballast member secured in place as by a screw, said ballast member having more weight on one side of the axis of the screw than it has on the other 85 side.
6. A golf club having in the head thereof 90 a cup member containing ballast material, which cup member is secured in place in said head as by means of a screw that passes through the center of the cup member, the ballast material being located in the cup member in such a manner as to effect an eccentric loading in respect to the screw.
7. A golf club having in the head thereof 95 a cup containing ballast material and which cup is secured in place so that it can be moved angularly with respect to a vertically extending axis whereby the ballast material can be moved toward and from the 100 striking face at the front side of the club.
8. A golf club having in the head thereof 105 a cylindrical-bore portion, a cylindrical cup member and a screw for securing said cup member in place, said cup member having one or more cavities or pockets in which there is lead secured in place.
9. A golf club having in the head thereof 110 a cylindrical bore and counter-bore open from the underside of the head, a cup having a bottom which enters the counter-bore portion and a flange which enters the cylindrical-bore portion, a screw passing through said cup and a socket in the upper portion 115 of the striking head into which socket the screw enters.
10. A golf club having in the striking head thereof a cup having an eccentrically located pocket for containing ballast material.
11. A golf club having in the striking head thereof an unsymmetrically weighted cylindrical member angularly adjustable.
12. In the ballasting of a golf club a method which comprises inserting lead or 125 other heavy fusible material in a removable cup until the required ballast is obtained, then melting the lead in said cup and securing the cup in place in the head.
13. A golf club having in the head there- 130

of a removable cup or receptacle having a plurality of ballast-receiving cavities therein.

14. A golf club having in the head thereof an adjustable cup member in which there are a plurality of cavities containing ballast material.

15. A golf club having secured in the head thereof an angularly adjustable eccentrically weighted member.

16. A golf club having a head comprising a wooden main body member, a wooden face member secured to the body member, and a wooden shoe member secured to the under side of said body member and to the under side of said face member so as to strengthen the head and assist in securing said body and face members together, the grain of the wood in the face member extending substantially at right angles to the striking face of the face member, the grain of the wood in the shoe member extending

from under the face member to under the body member in a manner to permit the shoe member to perform its above mentioned 25 functions.

17. A golf club having in the striking head thereof an eccentrically weighted member which is angularly adjustable.

18. A golf club having in the striking 30 head thereof a member which is eccentrically loaded with respect to an axis about which the member is angularly adjustable.

19. A golf club having in the striking head thereof an angularly adjustable member 35 which is eccentrically loaded with respect to the axis about which the member is adjustable.

This specification signed and witnessed this 4th day of May A. D. 1916.
